JEWELRY DISPLAY CABINET

Gerry Hansen, Glen Ridge, N.Y., assignor to
Richton International Corporation

Filed Nov. 17, 1975, Ser. No. 632,713

Term of patent 14 years

Int. Cl. D6—04; D20—02
U.S. Cl. D6—175

FIG. 1

FIG. 2

FIG. 3

FIG. 4

FIG. 1 is a front elevational view of a jewelry display cabinet showing my new design, it being understood that the cabinet has the same appearance in rear elevation;

FIG. 2 is a side elevational view thereof, it being understood that the cabinet has the same appearance from either side;

FIG. 3 is a top plan view thereof; and
FIG. 4 is a bottom plan view thereof.

I claim:

The ornamental design for a jewelry display cabinet, substantially as shown and described.
